UNITED STATES PATENT OFFICE

1,953,483

OIL BURNER

Arthur O. Higinbotham, Denver, Colo.

Application June 30, 1930, Serial No. 464,801

2 Claims. (Cl. 158—76)

My invention relates to oil burners. The principal object of the invention is to provide an apparatus that will completely and thoroughly mix the oil and air, in order that thorough combustion may be obtained.

Another object of the invention is to provide an apparatus for expelling air in a whirling, turbulent motion and to hold the oil mist or spray within a defined area, which permits complete combustion of same.

Heretofore, oil burners have projected mixtures of oil and air in a long, diverging stream. An important object of the present invention is to increase the diameter, and to decrease the length 15 of the flame; in fact, it is desirable that the flame be as large as the head of the burner.

A further object of the invention is to provide an air cushion immediately adjacent to the burner head, in order that particles of carbon 20 may be kept therefrom, to maintain the head in a clean condition.

Still further objects of the invention are to pre-heat air before it comes in contact with the oil mist, and to provide cross currents during the 25 mixing of the oil and air, in order to obtain the necessary turbulence.

Other objects reside in novel details, such as providing an air-cooled jacket for the burner head, and in novel combinations and arrangements of parts, which will appear in the course 30 of the following description.

In the drawing, like reference characters designate similar parts in the several views.

Figure 1 is an elevation of an embodiment of 35 the present invention.

Figure 2 is an enlarged section taken on the line 2—2 of Figure 1.

Figure 3 is a section taken on the line 3—3 of 40 Figure 2.

Figure 4 is a section taken on the line 4—4 of Figure 2.

Figure 5 is a reduced section taken on the line 45 5—5 of Figure 2.

Referring more in detail to the invention, a burner is designated generally by the reference 50 numeral 5. The burner is connected with a fan or blower 6 by means of an air conduit 7. An oil supply pipe 8 connects with a source of supply (not shown). The supply pipe has a restricted opening at the tip 9 for discharging oil in a mist or spray.

The burner head includes a face plate 10 containing a plurality of orifices 12 therethrough. The face has a flat ring 13 and a counter-sunk 55 portion 14, the latter containing the orifices 12,

The flat portion 13 also contains openings 15. Between an annular end plate 42 and the face plate 10 are placed vanes 17. These vanes are curved in section and provide a series of curved passages 18 for the escape of air. The vanes are 60 arranged around the periphery of the head, but spaced to allow free passage of air through the openings 15.

An air jacket 19 is provided for the burner head. The jacket has a recess 20 into which air is blown 65 in the operation of the device, to cool the jacket. The recess also lightens the weight of the jacket. The jacket has foot 21 adapted to slidably engage the burner head and particularly the vanes 17 thereof. The head is frictionally held in position 70 by the contact of the vanes on said foot. It will be apparent that the size of the openings 32 may be varied by movement of the burner head longitudinally relative to the jacket 19.

A spider 22, for holding the oil supply pipe 8, 75 and its attached nozzle 23 are fastened to the annular end plate 42 by means of bolts 24. A set screw 142 on the spider holds the pipe 8 in desired 80 positions relative to the face plate 10. The nozzle 23 and its associated supply pipe 8 may be moved to different positions by releasing the set screw 142. Spacing blocks 25 are provided therebetween.

The head also includes a housing tube 25 of non-conductive material for an electrode 26 of a 85 spark plug 27. The tube 25 has openings 28 and 29 at opposite ends for the passage therethrough of air, to keep the electrode tips clean. The electrode 26 and electrode 30 have a gap 31 to provide an electric spark. This gap is placed outside the 90 path of the oil projecting from the nozzle 23, so that after initial ignition takes place, continued combustion will not cover the electrode tips with carbon. The circuit for the spark plug is not shown, since it is thought to be well-known. The 95 spark is carried outward in the form of a loop toward the oil mist, by means of the air passing through the tube 25, since the electrodes are placed side by side with the gap 31 in the path of the air blast through the tube 25. A distinct advantage of this arrangement is that the spark is carried into the oil mist but the mist is not burned around the electrodes, which prevents fouling of the electrodes.

The nozzle 23 on the oil supply pipe has a 105 hexagonal collar 33. A sleeve 34 depends from the face plate 10 of the burner head. Slidably mounted in the sleeve 34 is a bushing 35 that carries a deflector 36. The sleeve and bushing have aligned apertures, as shown at 16. The deflector 110

affords an annular passage 37 which provides a converging air stream across face of the tip 9 of the oil nozzle, to keep same clean. Passages 38 are also provided by the deflector to project air across the counter-sunk portion 14 of the face plate, for the purpose of keeping carbon therefrom.

It will be seen throughout the description of the invention that precautions have been taken 10 to provide long life, by keeping the parts as clean as possible from carbon.

An important feature of the invention is the fact that the entire burner head may be taken out 15 as a unit when a plate 44 is removed from the air conduit. This feature is especially attractive when it is desirable to clean or repair parts of the burner. Taking out the burner head from the housing 7 does not disturb any of the adjustments of the burner head.

20 In the operation of the invention, the blower 6 is operated by any suitable means and propels air through the tube 7 and to and through the burner head. Air not only fills the recess 20 of the air jacket, but is also propelled through the longitudinally curved passages 18 between the vanes, 25 through the orifices 12 and openings 15, and through the non-conducting tube 25.

The small jets of air passing through the orifices 12, provide a cushion of air adjacent to the 30 face plate 10, while the passages 38 propel air across said face plate. The passage 37 projects air across the tip 9 at opposite points.

As stated above, the quantity of air traveling 35 through the passages 32 may be regulated by longitudinal movement of the burner head relative to the air jacket.

Air that is discharged through the openings 32 is directed forward on face 40 of the air jacket. The passages 18 give the air a whirling motion, 40 while the face 40 projects the air currents forward in an annular stream. Thus the air that is discharged from the burner head is in a whirling, annular stream. Passages 43 through the face 45 provide outlets for the air in the recesses 20. These passages 43 are arranged in a non-radial manner around the face 40.

In nature it is well-known that when air is propelled in such a manner, as in a whirlwind, there 50 are counter currents or eddies in the center traveling in the opposite direction. This is the result obtained in the present invention by actual tests.

Thus the oil mist discharged at the tip 9 of the oil nozzle is impinged upon by the air cushion at the face of the burner and the counter currents or 55 eddies effected by the annular stream of air. The oil mist caught therebetween is held in adjacency to the burner head, but is also subjected to a great

variety of currents and cross currents, which cause complete and thorough mixture of the air and oil. The oil mist is mixed with air at the inner surface of the annular stream of air. Moreover, the cross currents at the outer edge of 80 the burner head and across the face plate materially assist in mixing the air and oil.

The counter currents or eddies caused by the annular stream of whirling air are an important feature of the invention, for they effect the aforesaid thorough combustion and also keep the flame close to the burner head, with the result that a large, clean flame is produced. It has been found in actual practice that little or no carbon collects 90 on the nozzle, on the face of the burner head, or on the electrode tips, which, as stated before, causes long life and efficient service.

The arrows in Figure 2 only represent the directions of the air currents. To avoid confusion, 95 the direction of travel of the oil mist has not been noted. It is to be understood that any suitable nozzle 23 may be used for discharging a mist or spray of oil.

Due to the combustion of the oil taking place 100 in the vicinity of the burner face 10, this face and the thereto connected vanes 17 are heated to a considerable extent. Thus the air traveling through and around the face plate and between the vanes, is preheated before it comes into contact with the oil mist, which is an important feature of the invention.

It is to be understood that changes may be made in the construction, arrangement and combination of parts without departing from the spirit of the invention. I should, therefore, be accorded full protection against the use of all 110 equivalents.

What I claim and desire to secure by Letters Patent is:

1. In an oil burner, a source of air pressure, a 115 head having a curved passage for the discharge of air in a whirling motion, a nozzle for the discharge of an oil spray to be mixed with the air, and a deflector to direct air across the face of the nozzle, the head having an orifice for the passage therethrough of air to provide an air cushion for the head, the whirling air providing a counter current which together with the air cushion impinges upon the oil spray.

2. In an oil burner, an apertured burner head, 125 a nozzle for supplying an oil spray, and a deflector disposed to direct air across the faces of the head and nozzle, and a source of air pressure connected to direct air toward the deflector and through an aperture in the head to provide an air cushion 130 thereon.

ARTHUR O. HIGINBOTHAM.
